UNITED STATES PATENT OFFICE

1,991,259

SECURING FLOOR COVERINGS AND THE
LIKEBion C. Place, Detroit, Mich., assignor of one-half
to George E. Gagnier, Detroit, Mich.

Application July 29, 1931, Serial No. 553,875

13 Claims. (Cl. 72—101)

This invention relates to a new method and arrangement for securing floor coverings of various kinds. More particularly, the invention relates to an improved method and arrangement, whereby spring or snap fasteners may be utilized to secure floor coverings, as well as moldings that serve to provide a finished appearance, to the corners of the room, of the floor to which the covering is applied.

Heretofore floor coverings have been secured to the floor by means of driven or screw threaded fasteners, or by relatively complex snap fasteners of the type that include a member that is rigidly attached to the floor, and a complementary member that was secured to the rug. The former arrangements have the disadvantage of marring the floors and making it relatively difficult to apply and remove the floor covering. The latter arrangement permits the floor covering to be more readily removed, but they are not entirely satisfactory, not only because of the complexity of the fasteners, but because of the fact that the thickness of the assembled snap fastener is such as to cause protuberances in the floor covering at the points at which the fasteners are applied, resulting in excessive wear of the covering at such points. The latter arrangement also possesses the further disadvantage that the element of the fastener that is attached to the floor is liable to become bent making it difficult to bring about an interlock between the element carried by the covering and the element attached to the floor.

This invention aims to modify the corner construction between the wall and the floor in such a way, that the appearance of the corner is improved, and so that at the same time spring or snap fasteners, that are complete in themselves, may be utilized to secure the rug or covering as well as a molding used to provide a finished corner construction.

Another object of the invention is to provide a novel building construction in which the wall and the floor are separated by a gap that is bridged by a sheet metallic member provided with fastener receiving openings, which openings may be utilized to constitute the sockets to receive the shanks of unitary spring fasteners utilized to secure floor coverings or the like in proper position.

A still further object of the invention is to provide a molding that is preferably co-extensive with the edge of the floor covering to finish the corner of a room provided with a floor covering, which molding may be positioned by means of

snap or spring fasteners enabling it to be readily applied and detached.

A still further object of the invention is to provide a sheet metallic member for finishing a corner between the floor and wall of the room of a building, which member is so formed as to form a flush joint with the wall and with the floor, and so as to provide space to the rear of the member for the reception of the shanks of spring fasteners utilized to secure a molding, 10 floor covering or the like to said member.

Further objects of the invention will appear as a description thereof proceeds with reference to the accompanying drawings in which:

Figure 1 is a fragmentary vertical sectional view showing one preferred embodiment of the present invention.

Figure 2 is a fragmentary vertical sectional view, on an enlarged scale taken on the plane indicated by the lines 2—2 in Figure 3, the 20 molding and the clips or connectors and their fasteners being removed.

Figure 3 is a sectional view taken on the plane indicated by the lines 3—3 in Figure 2, looking in the direction of the arrows. 25

Figure 4 is a sectional view of a clip, and preferred form of fastener utilized to attach the molding to the member that bridges the gap between the floor and wall.

Figure 5 is a front elevational view of the clip 30 and fastener shown in section in Figure 4.

Figure 6 is a rear elevational view of the clip and fastener shown in Figure 4.

Figure 7 is a section of the molding taken on the plane indicated by the line 7—7 in Figure 8. 35

Figure 8 is a fragmentary elevational view of one form of molding.

Figures 9, 10 and 11 are respectively front, side elevation and top views of a spring fastener of the preferred type for securing the floor covering, molding, and the like. 40

Figure 12 is a fragmentary vertical sectional view showing a modified arrangement.

Figure 13 is a sectional view of the modified sheet metallic member utilized to bridge the gap 45 between the side wall and floor in Figure 12.

Like reference characters indicate like parts throughout the several figures.

By this invention, it is proposed to modify the corner construction of the rooms of buildings 50 and the like, so as to adapt the construction to receive resilient shanks of spring or snap fasteners, that are, preferably, utilized to secure the floor covering or a molding or both to said corner construction. In order that this may be 55

done it is essential that space be provided for the reception of the resilient shanks of said fasteners.

In the preferred embodiment of the invention, 5 10 indicates the floor of a room or the like supported on suitable supports such as joists 11. 12 indicates a side wall. As shown in Figure 1 the floor 10 terminates short of the wall 12 providing a gap between said floor and wall. A metallic 10 member 13 bridges the gap between said floor and wall. Preferably, the metallic member 13 is formed as shown in Figures 1 and 2 so as to provide a vertically extending attaching flange 14, a horizontally extending abutment 15 for a 15 base board 16 of the wall 12, a vertically extending portion 17 preferably disposed so that it forms a continuation of the outer face of the base board 16, an inclined portion 18, a horizontally extending portion 19 arranged so that its 20 outer surface is flush with the outer surface of the floor 10, a further vertical portion 20, constituting an abutment for the edge of the floor 10, and a horizontally extending attaching flange portion 21. Said metallic member 13 is 25 attached by suitably securing the flanges 14 and 21 to the wall and the floor supporting structure of whatever nature.

Said member it will be observed not only 30 bridges the gap between the wall and the floor, but it provides, to the rear thereof, a space of ample size to receive the shanks of the spring fasteners presently to be referred to.

The inclined portion 18 is provided with a 35 multiplicity of spaced perforations or openings 22 for the reception of the shanks of spring fasteners, while the horizontally extending portion 19 forming a continuation for the floor is provided with a series of spaced perforations 23 for a like purpose. Member 13, it will be observed further, provides a neat and finished 40 appearance for the corner between the floor and the wall, and it will be understood that said member is applied in said corner during the course of construction of the building, and that the openings or perforations 22 and 23 are included for the subsequent reception of fasteners intended to secure floor covering or a finishing 45 molding for the corner to said member 13.

When it is desired to secure a floor covering 50 24 in position the edges thereof are disposed to lap metallic members 13, which extend preferably around the entire room in the lower corners thereof, said covering lapping the horizontal portions 19 of said members. The floor covering is provided with openings 25 registering approximately with the openings 23 in said portion. Said openings in the floor covering may be reinforced by grommets as may be deemed 55 desirable.

60 The covering may then be attached to the portion 19 of the metallic member 13 by means of one-piece spring or snap fasteners, such as illustrated in Figures 9, 10 and 11 for example, though it will be understood that other spring 65 or snap fasteners may be employed, though it is essential that the fastener to be employed for this purpose include a head 26 and a resilient shank 27 projecting away from the head. The preferred form of fastener constructed from a 70 single piece of wire is fully described in my Patent #1,679,266, and consists briefly of a head in the form of a loop 28, formed by bending the mid-portion of the wire, of which the fastener is composed, into this form. The portions of the wire adjacent the ends of the loop are then

turned inwardly in the plane of the loop to provide arms 29 and 30. The ends of the wire are then bent at substantially right angles to the head thus formed, said ends forming the shank 27 of the fastener. In order to provide divergently disposed holding portions 31 and 32 and convergently disposed guiding portions 33 and 34, the ends constituting the shank of the fastener are bowed outwardly between the head 26 and the tips of the ends of the wire, as illustrated, and for the purposes more fully described in said patent. 5

The covering 24 is secured to the member 13 by inserting spring fasteners, such as described, though the approximately aligned openings 25 and 23 of the covering and member respectively. This may be brought about by simply inserting the fasteners through said openings and applying pressure to the head of the fastener inserting the fastener in a manner similar to the application of a thumb tack. The convergently disposed guiding portions 33 and 34 first engage the edges of the opening 23 causing a contraction of the shank of the fastener permitting the widest portions to pass through the opening. 20 After said portions have passed therethrough the divergently disposed portions 31 and 32 spring apart and the inclined portions thereof engage the edges of the perforation drawing the covering firmly toward the horizontal portion 19 25 of the member 13, thus holding the edge of the covering in position by a continuously effective yielding pressure.

The heads of the fasteners that hold the edges of the covering in position are then concealed, 30 and the whole corner is given a finished appearance, by the subsequent application of the molding 35 extending completely across the corner and concealing, not only the heads of the fastener, but, preferably the entire metallic 40 member 13. A preferred way of accomplishing the readily removable attachment of said molding is illustrated best in Figures 1, 4, 5 and 6 of the drawings. To accomplish this clips or connectors 36, illustrated in detail in Figures 4, 5 45 and 6 are employed. Each of said connectors includes a horizontally extended portion 37, a vertically extending portion 38, said horizontal and vertical portions being connected by the inclined portion 39. The extreme edges of the 50 portions 37 and 38 are turned slightly inwardly as shown at 40 and 41 for the reception of the margins of the moldings subsequently applied in the manner presently to be described. In order that said clips or connectors 36 may be 55 secured to the member 13 they are provided with fasteners of the kind illustrated in Figures 9, 10 and 11 or their equivalent. Preferably, said fasteners are assembled with respect to said connections by forming parallel slits 42 and 43 in 60 the inclined portion 39 thereof. The band of metal 44 separated from the clip or connector in this way is then bent inwardly so that the body of said band is spaced sufficiently therefrom, so that the head 26 of the snap fastener may be 65 inserted between the band and the rear face of the portion 39 as illustrated.

It will thus be seen that the clips may be readily provided with a spring fastener by simply inserting the portion of the head 26, to 70 one side of the shank 27, between the band 44 and the rear of the inclined portion 39 of the clip or connector. The spring fastener is thus held in position with respect to the clip and when pressure is applied to the clip, after the 75

shank 27 of the spring fastener is brought opposite an opening 22 in the inclined portion of the metallic member 13, assembly is brought about by pressing said shank in said opening. 5 The clip is thus attached to said member by snapping the resilient shank 27 into the socket provided by said opening 22 in the manner above described, in connection with the attachment of the edges of the floor covering.

10 It will be understood that the clips will be attached in this manner at intervals along the corners of the room. The molding 35, which may assume any ornamental external configuration, is preferably provided with inwardly turned edges 45 and 46 permitting the molding sections to be interlocked with the clips or connectors 36 either by hooking the edge 45 or 46 in back of the edge 40 of the clips or connectors and snapping the other edge of the molding past the edge 41 of the clip or connector that is immediately adjacent thereto, or the moldings 35 may be assembled with respect to the clips or connectors by telescopically sliding the inwardly turned edges 45 and 46 along the length of the 15 inwardly turned edges 40 and 41 of the connectors.

20 It will be observed that the molding can as readily be removed and that with this construction the edge of the floor covering as well as the fasteners that hold it in position are completely concealed by the molding providing a neat appearing and finished joint. The floor covering can as readily be removed and replaced. If desired metallic member 13 may serve as a 25 housing for electrical cables or similar conduits disposed in the corner of the room, and the removable hollow molding is likewise adapted to be used for the same purpose.

30 A modified form of the invention is illustrated in Figures 12 and 13 of the drawings in which the metallic member 13' bridges a gap between a baseboard 16' of a wall 12' and a floor 10'. The metallic member 13' includes attaching flanges 14' and 21', abutment 15' for the baseboard 16' and an abutment 20' for the 35 edge of the floor 10'. The portions 16' and 20' are connected by inclined portion 18' provided with a number of perforations or openings 47. Metallic member 13' thus differs from the member 13 previously described in that the vertical portion 17 and the horizontal portion 19 are omitted. The gap between the floor and molding is bridged by inclined portion 18' which is provided with fastener receiving openings 47. In this form of the invention the floor covering laps said openings in the inclined portion 18', and clips or connectors 36, a molding 35 and the edge of the floor covering are all secured by a single row of snap or spring fasteners as illustrated. Said fasteners are preferably of the type above described and they may pass through openings in the floor covering or the covering may be maintained unperforated and the edges clamped beneath the moldings.

40 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced 45 therein.

What is claimed and desired to be secured by United States Letters Patent is:—

5 1. In combination, a wall, a floor separated from said wall by a gap, a perforated metallic member formed to bridge the gap between said wall and said floor, and means including spring fasteners and a molding to secure a lapping covering to said member, said molding concealing said fasteners the shanks of which are snapped in the perforations of said member.

10 2. In combination, a wall, a floor separated from said wall by a gap, a perforated metallic member formed to bridge the gap between said wall and said floor, and means including spring fasteners, clips and a molding to secure a lapping covering to said member, said fasteners holding said clips yieldingly and removably to said member and said molding being held by said clips by being sprung beneath the edges thereof.

15 3. In combination, a wall, a floor separated from said wall by a gap, a sheet metal member having an inclined portion extending across the corner between said floor and wall and bridging said gap so as to provide a space in back of said portion, and means including spring fasteners the resilient shanks of which extend through said portion into said space to secure a 20 floor covering to said member.

25 4. The combination defined in claim 3 in which said sheet metal member is formed to provide an abutment for said floor making a flush joint between said floor and member.

30 5. The combination defined in claim 3 in which said sheet metal member is formed to provide an abutment for the baseboard of said wall making a flush joint between said member and baseboard.

35 6. The combination defined in claim 3 in which said sheet metal member also includes a horizontal shelf portion constituting a continuation of the floor.

40 7. The combination defined in claim 3 in which said sheet metal member also includes a vertically extending portion forming a continuation 45 of a baseboard and an abutment forming a rest for said baseboard.

45 8. In combination, a wall, a floor separated from said wall by a gap, a sheet metal member bridging said gap and having portions flush 50 with the adjacent portions of said wall and floor, spring fasteners to secure a lapping covering to one of said portions, and a molding concealing said spring fasteners and said member, said molding being also secured to said member by spring fasteners.

55 9. The combination defined in claim 8 in which said member includes an inclined portion perforated to receive said second named spring fasteners.

60 10. In combination, a wall, a floor separated from said wall by a gap, a sheet metal member bridging said gap and forming a smooth joint with said floor and wall, a molding to lap an edge of a floor covering, and spring fasteners 65 to secure a lapping floor covering and said molding to said member.

65 11. A sheet metal member to facilitate attachment of carpets to floors by means of spring fasteners, consisting of a body portion provided 70 with fastener receiving openings and edge portions disposed at an angle to the body portion and provided with means to secure said edge portions to a building, said edge portions serving to space said body portion from the parts 75

of the building to which it is attached so that space is provided in back of said body portion for the reception of the shanks of spring fasteners.

- 5 12. In combination, a wall, a floor separated from said wall by a gap, a metallic member formed to bridge the gap between said wall and floor, means to space said member from said wall and floor, and means including spring fasteners to secure a lapping covering to said member and projecting into the space behind said member.

13. In combination, a wall, a floor separated from said wall by a gap, a perforated metallic member formed to bridge the gap between said wall and said floor, means to space said member from the corner between said wall and floor, and means including spring fasteners having their shanks snapped into the perforations in said member, and extending into the space behind said member to secure a lapping covering to said member.
